DOOR-CONTROLLING MEANS

Andrew C. Dunn, Chicago, Ill., assignor to O. N.
Davies, trustee, Minneapolis, Minn.

Application December 16, 1935, Serial No. 54,657

4 Claims. (Cl. 268—66)

This invention relates to controlling doors, and is of special utility in controlling the opening and shutting of relatively heavy doors subject to considerable variations in the wind pressure against them, as for example the doors of 5 apartments and hotels especially those on the upper floors, and the street doors of shops and the like.

The fluid door checks usually used with such 10 doors require different settings for different wind pressures, and consequently when that pressure varies from the pressure for which the door check is adjusted, the door check will either let the door slam or it will unduly retard or entirely stop the closing.

According to my invention, the door is controlled during the final part of its closing movement and the first part of its opening movement by novel devices which do not act on the door 20 during the remainder of its movement, and which can consequently be adjusted to control the door accurately under the heaviest pressures without making an undue burden of opening and closing the door.

I prefer to utilize also, as a cooperating control device, the usual fluid door check or one of the improvements thereon described below. However, since the door check no longer has the 30 entire burden of closing the door and holding it closed and of preventing slamming, it may be adjusted for easy operation in opening the door and to close the door sufficiently for my novel control devices to take charge of it, as the door is relatively easy to control when it is partly open.

My novel control devices include a check device of the type having a cylinder and piston arranged to have a dashpot effect in retarding the final closing of the door and preventing 40 slamming, and the cylinder of which preferably has an integral extension formed with a cam surface controlling the action of a spring door closer. The door closer illustrated is of novel construction, including pivotally-connected parts 45 arranged to form a housing or casing for the door-closing spring.

An important feature of the invention relates to supplying a power medium, such as compressed air, for operating one or more of the 50 control devices to open the door by power. Preferably the compressed air, or equivalent medium, acts on my novel check device to give a quick opening push, and also acts on the door check to follow this up with a sustained opening thrust 55 acting more slowly. Various features of the in-

vention relate to the construction and arrangement of the check device and of the door check, to secure this action.

This phase of the invention also has to do with the control of the power, as for example by mounting in the door a control device such as a compressed-air valve which is actuated by pulling or thrusting at the door to open it, and which is closed again automatically by the consequent opening of the door. Thus the natural motions 10 of opening and closing the door serve to perform those operations, but by controlled power.

If desired, for shop doors and the like, the control may be from novel circuit closing devices arranged in the floor on opposite sides of the 15 door, where they are walked over in approaching the door. In this case, the circuit includes means holding the door open for a sufficient interval for a person to walk through it.

The above and other objects and features of 20 the invention, including various novel combinations of parts and desirable particular constructions, will be apparent from the following description of the illustrative embodiment shown in the accompanying drawings, in which:

Figure 1 is a perspective view of a door and its casing, with my novel controls;

Figure 2 is a section longitudinally through the door check shown in Figure 1;

Figure 3 is a partial section on a larger scale 30 than Figure 2, showing the check valve arrangement;

Figures 4 and 5 are sections corresponding to Figure 2, but showing modifications of the door check;

Figure 6 is a partial top plan view of the door and the check device and door closer, with the cylinder of the check device partly in section;

Figure 7 is a section through my novel spring door closer, on the line 7—7 of Figure 6;

Figure 8 is a partial section through the door closer on the line 8—8 of Figure 7;

Figure 9 is a perspective view of a cam device for use in the door closer;

Figures 10, 11, and 12 are diagrams showing 45 the compressed air hookup when the door checks of Figures 2, 4, and 5 respectively are used;

Figure 13 is a partial section through the door handle, showing the control valve;

Figure 14 is a diagrammatic section showing 50 an electrically-controlled valve operated by walking over a novel contact-making device laid on the floor;

Figure 15 is a partial section through the contact-making device of Figure 14; and

Figure 16 is a detail section through an adjustable-bleed check valve used with my control devices.

My novel control devices are shown as used 5 to control the opening and closing of a door 10 pivotally mounted in a door casing 12 by means such as hinges 14 secured to its edge.

Connected between the door and the casing is 10 a door check including a casting 16, shown bolted or otherwise secured to the door, and which contains a torsion spring 18 secured to the casting at one end and secured at its other end to a rotatable shaft 20 on which, outside the casting 16, is fixedly secured an arm 22 pivoted at its 15 end to one end of a link 24. The other end of the link 24 is pivoted to a bracket 26 mounted on the casing 12. The parts may of course be reversed, the casting 16 being mounted on the casing and the bracket 26 on the door. When 20 the door is closed, the arm 22 and the link 24 are arranged beside each other.

The casting 16 is formed with a cylinder 28 for pistons 30 and 36 having a piston rod 32 formed with a rack operatively meshing with and driving a pinion secured on the shaft 20. The cylinder 28 contains a suitable liquid such as oil, which as the door closes is forced by the piston 36 through a passage 34 into the opposite end of the cylinder behind the piston 30, past an 30 adjustable needle valve 40 (Figure 3).

When the door is closing, the oil pressure holds a ball check valve 42 on its seat, so that all the oil must pass the needle valve 40, while when the door is opening the oil can readily pass the check valve 42 and the device offers only the resistance of spring 18 to the opening of the door.

A second piston rod 44 extends from auxiliary piston 36 through a packing in the end of the cylinder 28, and is operatively connected to a power piston 46 arranged in a power cylinder 48 (of larger diameter than cylinder 28) secured on the casting 16 coaxially with respect to cylinder 28. The cylinder 48 is provided with an inlet port 45 communicating with a compressed air conduit 50.

The door check described above is operated in opening the door, by the power of compressed air acting as hereinafter described on the piston 46, to shift the piston rod or rack 32 to the left in 50 Figure 2, to cause the arm 22 to thrust through the link 24 in a direction to open the door, and at the same time to wind up the spring 18. When the air pressure is released, the spring 18 acts to close the door against the dashpot action of the 55 piston 36 forcing the oil past the needle valve 40.

As previously explained, in order to obviate the necessity of making the doordcheck act powerfully enough when the arm 22 reaches an ineffective angle, just as the door closes, and to insure 60 against slamming without unduly slowing up the major part of the closing movement, I provide a novel cooperating check device including a cylinder 52 adapted to be secured to the door, and provided with a piston 54 having a thrust rod 56 with 65 a rounded end adapted to engage a leather or cork bumper carried by a fitting 58 secured to the casing 12. The cylinder 52 may of course be secured to the casing instead of to the door, in which case the bumper 58 would be mounted on 70 the door.

The preferred construction is shown in detail in Figure 6. The piston 54 is shown as a metal stamping backed by a leather seal or cup 60 held against the cylinder wall by a compressible felt 75 ring 62. A second stamping 64 is flared to engage

the cylinder wall further back, to give a more extended bearing on the cylinder.

The illustrated cylinder includes a cylindrical steel liner 66, on which one end of the cylinder is cast as a cap permanently secured thereto, and on which the other end is detachably threaded as a removable cap providing a bearing for the thrust rod 56.

When the door is opened, a spring 68 urges the piston 54 to the end of the cylinder, drawing air 10 past a ball check valve 70 (Figure 16) in a valve casing 72. When the door closes, the piston 54 gradually forces the air out, with a dashpot action, past an adjustable needle valve 74 in the casing 72, the ball valve 70 being at that time 15 held on its seat by the air pressure.

If desired, one of the valves 72 may also be interposed between cylinder 48 and conduit 50, to make the piston 46 and cylinder 48 also act as a dashpot as the door closes.

According to one feature of the present invention, compressed air or an equivalent power medium is caused to act on the piston 54, by being introduced into the cylinder 52 through a conduit 76, to give the door an opening push, after which 25 the opening is completed by the more gradual action of piston 46 acting alone. This operation has the further advantage that there is a great deal more air in the cylinder 52 which has to be forced gradually out in closing the door, making 30 the dashpot action that much more effective.

The detachable cap of the cylinder 52 is shown as formed with an integral extension 78. This extension, and a cap 80 detachably secured thereto, form a housing, open at the top, within which 35 is adjustably secured a plate 82 formed with parallel curved flanges 84 and 86 forming a cam track for a cam roller 88 or the like.

The plate 82 also has a slotted projection 90, in the slot of which is seated the central portion 40. of a U-shaped leaf spring 92, the two arms of which rest against the inner walls of the flanges 84 and 86 respectively. The two arms of the spring 92 spring away from these flanges sufficiently so that the arm on the left in Figure 6 45 serves to cushion the impact of the roller 88 as it enters the cam track between flanges 84 and 86 as the door is closing. The spring also serves to take up play between the roller and the cam track.

The cam device 82 can be adjusted, according to the position of the roller 88, being held by screws 94 passing through slots 96.

The roller 88 has a spindle 98 by which it is mounted on one part 100 of a substantially closed 55 two-part casing. The casing part 100 is the movable element of the door closer, and is connected by alined pivots 102 to the stationary casing part 104 secured to the door casing 12.

A strong coil spring 106 is housed within this 60 casing or housing 100-104 being tensioned between a pin 108 carried by the stationary part 104 and a nut 110 adjustably threaded on a bolt 112 having a semispherical head seated in a socket formed in the end of the casing part 100. The 65 righthand end of the spring 106 is also shown secured to the pin 108 by being attached to a nut 114 threaded on a bolt 116 having its head formed as an eye sleeved on the pin 108.

When the door opens, the cam 84-86 acts on 70 the roller 88 to rock the casing part 100 about the axis of pivots 102, to tension the spring 106, and also to shift it slightly past a dead-center position, where it holds the casing part 100 against a stop formed by a flange 118 on the sta- 75

tionary casing part 104 (Figure 8). The closing of the door causes cam flanges 84-86 to reengage the roller 88, and as soon as spring 108 is shifted past dead center it acts as a powerful force to insure the firm closing of the door, and to hold it closed tightly without rattling.

As shown in the diagram of Figure 10, the conduits 50 and 76 may be connected through a suitable control valve 120, and through a suitable 10 swivel joint 122 permitting the swinging of the door, and through a pressure regulator 124 if desired, to a reservoir 126 kept charged with compressed air by means such as a motor-driven automatic compressor 128.

15 In Figure 13, in lieu of the simple three-way valve 120 of Figure 10, I substitute a plunger valve 130 urged by a spring 132 to the illustrated position in which the conduits 50 and 76 are connected to an exhaust port 134. The plunger 20 130 may be shifted, to connect the conduits 50 and 76 with a conduit 136 communicating with the reservoir 126, either by pressure on a thrust member 138 pivotally mounted on one side of the door, or by tension on a handle 140 pivotally 25 mounted on the other side of the door.

It will be noted that this gives the door a "follow-up" action. As soon as one presses on the plate 138 or pulls on the handle 140, the door opens, and this acts to close the valve 130 again 30 unless one continued to push or pull (as the case may be) still further.

In Figures 14 and 15 I illustrate an arrangement in which one opens the door by walking over a novel contact making device comprising 35 plates 140 and 142 separated by sponge rubber 144 and provided with contacts 146 which are closed by compressing the sponge rubber. This closes a circuit between wires 148 and 150 (or 152 and 154 in parallel therewith), causing current to flow from a transformer or other source 40 156 through a coil 158. The coil 158 has a stationary lower core 160, which draws downwardly a movable core 162 which operates the valve plunger 130.

45 The movable core 162 has a thrust part 164 which acts to close a contact between a spring finger 166 and a thermostatic strip 168 connected, through a heating resistance 170 adjacent the thermostatic or bimetallic strip 168, to the 50 wires 148 and 150.

As long as the contacts 146 remain closed, the door stands open and substantially no current passes through the resistance 170. As soon as the person who closed the circuit proceeds 55 through the door, the contacts 146 separate, and the current through the coil 158 passes through the resistance 170. After a suitable interval, the heat from the resistance 170 causes the strip 168 to warp away from the strip 166, breaking the 60 circuit and causing the door to close.

In the arrangement illustrated in Figures 4 and 11, the compressed air acts on a power piston 180 in the door check 182, actuating a piston rod rack 184 corresponding to the rack 32, and compressing air trapped in a cylinder 186 ahead of a piston 184, thus eliminating the oil used with the device of Figure 2. When the door is closed, air can enter cylinder 186 through a port 190.

70 In the arrangement of Figures 5 and 12, the doorcheck 192 contains a large piston 194 and a small piston 196 connected by a piston rod rack 198 geared to a shaft 200 which corresponds to the shaft 20 in Figure 2. The piston 194 is acted on by air from the conduit 50 controlled by 75 valve 120, as before, but the piston 196 is ar-

ranged in a small cylinder 202 communicating continuously, by means such as a conduit 204, with the reservoir 126.

This substitutes, for the spring 18, the elastic force of the compressed air in the reservoir 126 5 and the conduit 204. When valve 120 (or 130) is operated to open the door, there is eventually built up the same pressure per square inch on the piston 194 as on the piston 196, but since the piston 194 is the larger it shifts the piston 10 196 to the left in Figure 5, opening the door. When line 50 is exhausted to the atmosphere, the elastic pressure on the piston 196 closes the door.

While various illustrative structures and arrangements have been described in detail, it is 15 not my intention to limit the scope of my invention by that description, or otherwise than by the terms of the appended claims.

I claim:

1. Door-controlling means comprising, in combination with a door, and its casing, a door check connected between the door and casing and having an arm and a link forming said connection, and which door check includes a power means for rocking said arm to open the door, a check 20 device operable between the door and casing during the last part of the closing movement and the first part of the opening movement of the door and which yieldingly retards the final closing movement of the door and which is operable by 25 power to give an opening push to the door, a door closing device engageable between the door and its casing and operable to force the door closed while said check device is retarding the closing of the door and which includes a spring 30 which is tensioned by the opening of the door, and common control means for the power operation of the door check and said check device to cause synchronized operation thereof to open the door. 40

2. Door-controlling means comprising, in combination with a door casing and a door pivoted at one edge therein, a door check connected between the door and the casing and including an arm and a link connected to the arm, said arm 45 and link being arranged beside each other when the door is closed, said door check having fluid power means for rocking said arm in a direction to thrust on said link to open the door, a check device engaging between the door and casing during the final part of the closing movement and the first part of the opening movement of the door without interfering with the remainder of the movement of the door, said check device comprising a cylinder and piston 50 having a dashpot action yieldingly retarding said final closing movement as said arm and link reach a relatively ineffective angle and having connections supplying power fluid to said cylinder to give an opening push to the door during 60 said first part of the opening movement while said arm and link are still at a relatively ineffective angle with respect to each other, a door closing device including parts on the door and the casing which engage each other during 65 the final closing movement and the first opening movement of the door and one of which parts includes a substantially closed casing in two pivotally connected sections and a spring housed in said casing and arranged to be tensioned by the first part of the opening movement of the door and to close the door against the yielding retardation of the door check and the check device during the final part of the closing movement of the door, and common control means for sup- 70

75 75

plying power fluid to the door check and the check device.

3. A door swingable about a vertical axis and provided with a fluid-power opening device having a control valve including a spring-closed valve plunger arranged to extend through the door, a handle on one side of the door movable toward and away from the plane thereof and connected to open said valve by pulling on one end of the plunger when tension is applied to the handle in the direction of opening of the door, and a thrust member on the other side of the door operable when pushed against in the direction of opening of the door to open the valve by pressure on the other end of the plunger.

10 4. Door-controlling means comprising, in com-

bination with a door swingable about a vertical axis, a fluid power device for opening the door, a control valve for the power device carried by the door, and an operating member for the valve connected to the door and movable toward and 5 away from the plane of the door and arranged to be shifted relative to the door in the direction of opening movement of the door to move the control valve to cause the door to open and to be shifted in the opposite direction by the consequent movement of the door relative to the operating member to move the valve toward a lapped position to retard further opening of the door.

10 ANDREW C. DUNN. 15
